CLAIM

The ornamental design for a convertible hood for caster, as shown and described.

DESCRIPTION

FIG. 1 is a perspective view of a convertible hood for caster, showing a typical embodiment of my new design.

FIG. 2 is a reduced scale left-side elevational view thereof.

FIG. 3 is a top plan view thereof.

FIG. 4 is a right side elevational view thereof.

FIG. 5 is a bottom plan view thereof.

FIG. 6 is a front elevational view thereof.

FIG. 7 is a rear elevational view thereof; and,

FIG. 8 is an environmental left side elevational view thereof with the broken line showing of part of a caster body and a wheel being for illustrative purposes only and forming no part of the claimed design.
